UNITED STATES PATENT OFFICE.

LEE T. ALTON, OF NEW YORK, N. Y.

DESIGN FOR AN INCANDESCENT GAS ARC-LAMP OR SIMILAR ARTICLE.

SPECIFICATION forming part of Design No. 34,087, dated February 12, 1901.

Application filed January 19, 1901. Serial No. 43,954. Term of patent 14 years.

To all whom it may concern:

Be it known that I, LEE T. ALTON, a citizen of the United States, and a resident of the city of New York, borough of Brooklyn, county of 5 Kings, and State of New York, have invented and produced a new and original Design for Incandescent Gas Arc-Lamps or Similar Articles, of which the following is a specification.

The drawing illustrates a side elevation of 10 the lamp.

The essential features consist in the shape and correlation of the various parts one to the other.

Viewed in its aspect of shape, the lamp 15 comprises the cylindrical rod 1, having the surmounting circular cap 2, an intermediate circular ornament 3, and a bell-shaped cap 4,

from which extends the cylindrical rod 5, passing into the globular body 6, from which is mounted a circular ring 7, having the ornamental upper edge 8. Below the body 6 there is an inverted-bell-shaped circular piece 9, having an outwardly-extending link-shaped part 10.

Having described my invention, I claim— 25

The design for an incandescent gas arc-lamp or similar article, substantially as herein shown and described.

Signed at the city, county, and State of New York this 7th day of January, 1901.

LEE T. ALTON.
